UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

Application filed August 16, 1923. Serial No. 657,656.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States to O. Mergenthaler No. 436,532, wherein circulating matrices are released from a magazine in the order in which their characters are to appear in print, and then assembled in line, the composed line transferred to the face of a mold, the mold filled with molten metal to 20 form a slug or linotype against the matrices which produce the type characters thereon, and the matrices thereafter elevated and returned through distributing mechanism to the magazine from which they started.

25 More particularly, it relates to machines of the kind presented in prior Letters Patent Nos. 1,309,416; 1,373,942 and 1,433,087, wherein the matrix magazines are arranged side by side or in "tandem," and wherein 30 the matrices are drawn from the different magazines by the manipulation of a single keyboard common to them all.

The present invention is directed to certain improvements in machines of the class 35 stated, as will be fully set forth in the detailed description to follow.

In the accompanying drawings, I have illustrated my improvements merely in preferred form and by way of example, and as 40 applied to the particular style of machine mentioned, but obviously many changes and variations may be made therein, and in their mode of application, which will still be comprised within the spirit of my invention. 45 Further, my improvements are readily adaptable to other forms of typographical machines, such as those that handle type or dies, instead of matrices. Generally speaking, I desire it to be understood that I do 50 not limit myself to any specific form or em-

bodiment, except in so far as such limitations are specified in the claims.

Referring to the drawings:

Fig. 1 is a front elevation of a linotype machine equipped with my improvements; 55

Fig. 2 is a vertical section taken on the line 2—2 of Fig. 1;

Fig. 3 is a transverse section taken on the line 3—3 of Fig. 2 looking downwardly;

Fig. 4 is a detail perspective view of one 60 of the keyboard connecting bails and the associated escapement actuating reeds;

Fig. 5 is a vertical section taken through the auxiliary magazines and their escapement actuating devices; 65

Fig. 6 is a view similar to Fig. 5, but showing a modified arrangement of the escapement actuating devices;

Fig. 7 is a perspective view of a detail;

Fig. 8 is a diagram showing the complete 70 layout of the connections between the escapement actuating reeds of the main and auxiliary magazines;

Fig. 9 is a perspective view showing an improved operating means for the space-band escapement; 75

Fig. 10 is a front view showing a key-operated shift for the escapement actuating reeds of the main magazine; and

Fig. 11 is a vertical section taken on the 80 line 11—11 of Fig. 10.

In the embodiment illustrated, which is given purely by way of example, the matrices X of the regular fonts are stored in two superposed main magazines A, while 85 the matrices Z of the supplemental fonts are similarly stored in two superposed auxiliary magazines B, the latter being arranged at the side of or in tandem with the main magazines. The main magazines 90 A are of the customary trapezoidal form, each having its grooved channels (ninety in number) converging toward its lower end and spaced apart to accommodate the smaller matrices of the regular fonts; 95 whereas, the auxiliary magazines B are of plain rectangular shape, each having its grooved channels (thirty-four in number) parallel throughout and more widely spaced apart to accommodate the larger matrices 100

of the supplemental fonts. Cooperating with the magazines, is a common assembler entrance having a main portion C arranged to receive the matrices X from a selected 5 one of the main magazines A, and an auxiliary portion C¹ arranged to receive the matrices Z from a selected one of the auxiliary magazines B, it being observed that both portions C and C¹ discharge the matrices 10 onto an assembling belt C², which delivers them to an assembler C³, wherein they are composed in line. Both the main and auxiliary magazines are movably mounted so that by the operation of hand 15 levers A¹ and B¹, any selected pair may be brought into operative relation to the common assembler entrance. Any of the well known forms of mounting may be employed for this purpose, such as that embodied in 20 the commercial Model 14 machine, but it is preferred to make use of the particular form of mounting shown and described in my prior Letters Patent No. 1,459,978, which latter form is of such character as 25 to permit the shifting of the magazines without disturbing their operative connection with the distributing mechanism.

Each of the main magazines A is provided with a set of matrix releasing escapements 30 A², one for each channel thereof. These escapements, or rather those belonging to the magazine in operative position, are actuated by a corresponding set of vertically movable reeds A⁴ which act thereon through intermediate pivoted levers A³ of customary form. The reeds A⁴ are supported at their 35 lower ends upon a transverse bar A⁵ and are guided in their vertical movements by upper and lower comb-plates A⁶ and A⁷. At 40 this point, it may be noted that the guiding slots in the upper comb-plate A⁶ are long enough to permit certain of the reeds A⁴ to be swung forwardly and backwardly about the supporting bar A⁵ into and out of engaging 45 relation to the pivoted levers A³, for reasons which will subsequently be explained. The raising of the reeds A⁴, to carry out the escapement releasing operation, is effected, as usual, by means of pivoted yokes or levers A⁸ arranged in two 50 banks or series and with their inner ends in position to engage the lower ends of the reeds A⁴. These yokes or levers A⁸ are provided with cams or eccentrics A⁹ adapted to be 55 engaged with and rotated by underlying power driven rolls A¹⁰, such engagement of the parts being controlled by trip dogs A¹¹ connected by vertical actuating slides A¹² to finger keys of the keyboard A¹³. The operation 60 of these parts is so well known that any further description would be superfluous.

Each of the auxiliary magazines B is likewise provided with a set of matrix releasing escapements B², one for each channel there- 65 of, but in this instance the actuation of the escapements of the operative magazine is effected by means of a second set of comparatively short vertically movable reeds B⁴ having their upper ends coterminous with those 70 of the main reeds A⁴, and acting on the escapements through intermediate pivoted levers B³, duplicates of the levers A³. These reeds B⁴ (unlike the reeds A⁴) are arranged in constant engaging relation to the pivoted 75 levers B³, being supported at their lower ends upon a transverse bar B⁵ and guided by upper and lower comb-plates B⁶ and B⁷, which permit of a vertical motion only. Springs B⁸, pulling downwardly on the 80 reeds B⁴, serve to maintain them in their normal position of rest and to depress them after being raised to actuate the escapements B². Such raising of the reeds B⁴ is effected through suitable connections 85 from the main keyboard A¹³, as will now be described.

Arranged at the rear of the two sets of actuating reeds, are a series of transverse substantially U-shaped rocking bails D, adapted to connect corresponding actuating reeds of the two sets, such that when any given one of the main reeds A⁴ is raised by the actuation of the associated finger key, the motion thereof will be transmitted 90 through the appropriate connecting bail D to the corresponding auxiliary reed B⁴. There are as many such bails D as there are actuating reeds B⁴, or thirty-four in all, and each of said bails presents at its opposite 95 ends two parallel arms D¹ and D², respectively, for engagement with the corresponding reeds of the two sets which it is intended to connect (see Fig. 3). In the embodiment 100 here illustrated, the arms D¹ (Fig. 5) are located below and in constant engaging relation to projecting lugs b⁴ on the rear edges of the reeds B⁴, while the arms D² (Fig. 2) are located above reversely disposed projecting lugs a⁴ on the rear edges of the corresponding reeds A⁴ and in position to be 105 engaged with or disengaged from said lugs according to the position of the reeds A⁴, it being remembered that these particular reeds are mounted so as to be swung forwardly 110 and backwardly into and out of engaging relation to the pivoted levers A³.

As a result of the foregoing construction, when the reeds A⁴ of the group concerned 115 are located in their forward position, they are disengaged from the rocking bails D and act only upon the pivoted levers A³ to actuate the escapements of the main magazine in use, the condition shown by the full lines in Fig. 2; whereas, when said reeds are located in their rearward position, they are out of 120 engaging relation to the pivoted levers A³ and (by the engagement of their projecting lugs a⁴ with the arms D²) act only upon the bails D, which transmit the upward motion 125 130

thereof to the reeds B^4 for the actuation of the escapements of the auxiliary magazine, the condition shown by the dotted lines in Fig. 2. In this way, and simply by shifting 5 the actuating reeds forwardly and backwardly, the single keyboard may be caused to release matrices from the operative main or auxiliary magazine, as desired. As the magazines are mounted so that any selected 10 pair may be brought into operative position, it follows, of course, that by shifting both the magazines and the actuating reeds, the keyboard may be operatively connected to any selected one of the different magazines. 15 It will be understood that when the keyboard is connected to an auxiliary magazine, only part of the finger keys are effected, the others maintaining their connection with the main magazine in use at the time. This feature 20 is quite advantageous under certain conditions, in that it enables matrices to be drawn from both a main and an auxiliary magazine simultaneously.

In the present embodiment, both auxiliary 25 magazines are devoted to a single font of matrices Z , one-half of which is stored in each. The arrangement of the characters in the two magazines is illustrated in Fig. 8. For the most part, as will be noted, matrices 30 with like characters occupy similarly located magazine channels, this being true of all the characters with the exception of those stored in the first ten channels, which differ as between the two magazines. To 35 provide for this different character arrangement of the matrices, some of the finger keys of the keyboard are each provided with two different index characters, one representing the matrix contained in the upper magazine, and the other representing the matrix contained in the lower magazine, as clearly illustrated in Fig. 8. In the other cases, however, the index characters representing the matrices stored in the different 40 magazines are placed on different finger keys. For this reason, a few of the rocking bails D (four, to be exact) are each provided with a third arm D^3 to adapt them to cooperate with two different actuating reeds A^4 . Fig. 4 shows one of such three-armed bails, and, as will be seen, it serves to connect two different finger keys A^{13} with one and the same actuating reed B^4 . In this illustration, the actuating reed 45 represented is the first one of the auxiliary set (controlling the release of matrices bearing the numeral 1 from the upper magazine and matrices bearing the lower case letter q from the lower magazine), and hence the two finger keys are shown as provided with corresponding index characters, the key at the left serving to release the numeral 50 matrices, and that at the right the lower case matrices. The other three actuating reeds B^4 having bails of the same form are 55 the second, third and tenth ones of the auxiliary set, these reeds controlling the release of matrices bearing the characters 2, 3 and 0 in the upper magazine, and matrices bearing the characters x , z and $\$$ in the lower magazine, respectively. The different pairs of finger keys which effect the operation of these three auxiliary actuating reeds are shown with the corresponding index characters in the diagram of Fig. 8. In fact, the layout of the entire arrangement is 60 illustrated in this figure, and the connections from any one of the finger keys can be easily traced. It is, therefore, believed to be unnecessary to discuss the matter any further.

Referring now to the bails D , they are enclosed within a box or casing J , and are mounted in superposed relation upon a smaller number of pivot rods J^1 , each of which is common to a plurality of bails, thus affording a neat, compact arrangement of the parts and avoiding interference with other parts of the machine. The pivot rods J^1 are fitted detachably into the side walls 65 of the box or casing J , and the arms of the bails project forwardly through slotted openings in the front wall thereof, so as to make engagement with the actuating reeds of the two sets, in the manner before described. The slotted openings formed in the front wall of the box or casing, are long enough to permit a limited rocking movement of the bails, such as is required in 70 transmitting the motion of the main actuating reeds A^4 to the auxiliary actuating reeds B^4 . The box or casing J is detachably connected to the framework, as by means of screws or similar fastening devices, so that it with the contained parts 75 may be applied to or removed from the machine as a unit, the loose engagement between the bail arms and the actuating reeds being made and broken as the unit is applied or removed.

The fore and aft shifting of the main actuating reeds A^4 , as above described, may be effected in any suitable manner. As a simple means for this purpose, there is provided a horizontally movable slotted guide frame E , shown in detail in Fig. 7, through which the reeds pass and which is provided with a handle E^1 to facilitate its manual adjustment. If desired, a spring detent E^2 80 may be employed to hold the guide frame in either its forward or rearward position. In Figs. 10 and 11, which show an alternative arrangement, the position of the guide frame E is controlled by means of a finger key E^3 located directly above the keyboard A^{13} and connected to the frame through a vertical slide E^4 , connecting link E^5 and pivoted bell crank lever E^6 . A spring E^7 85 pulling upwardly on the finger key acts constantly to hold the guide frame in its 90

forward position, so as to cause the reeds A^4 to release matrices from the main magazine only. The depression of the finger key, however, against the action of the connect-
 5 ed spring, will shift the guide frame to its rearward position and cause the actuating reeds to release matrices from the auxiliary magazine only. A slotted plate E^8 , having a lateral locking notch E^9 , is associated
 10 with the finger key E^3 to hold it depressed whenever it is desired to do so.

Fig. 6 illustrates a modified arrangement, wherein the rocking bails D are connected to the auxiliary actuating reeds B^4 by power
 15 driven elements set into action by the operation of the main actuating reeds A^4 . These power driven elements are similar to those employed for operating the main reeds A^4 , each comprising a pivoted yoke or lever B^9 ,
 20 provided with a rotary cam or eccentric B^{10} , adapted, in response to the actuation of a trip dog B^{11} , to be engaged with and rotated by an underlying power driven roll B^{12} . The trip dogs B^{11} are connected to
 25 the lower ends of vertical actuating slides B^{13} arranged directly behind the reeds B^4 and in constant engagement with the arms D^1 of the rocking bails D . These actuating slides B^{13} are supported at their lower
 30 ends upon a transverse bar B^{14} and are guided in their vertical movements by the comb-plates B^6 and B^7 , which serve to guide the reeds B^4 . Springs B^{15} are connected to the slides B^{13} and serve constantly to hold
 35 them depressed. According to this arrangement, therefore, when one of the main reeds A^4 is raised by the operation of the associated cam yoke A^8 , in response to the actuation of the corresponding finger key A^{13} ,
 40 the upward movement of that reed will be transmitted through the appropriate bail D to the connected actuating slide B^{13} , which thereupon trips the cam yoke B^9 and causes it to raise the corresponding auxiliary reed
 45 B^4 , the springs B^8 and B^{15} acting to depress the reed B^4 and slide B^{13} , respectively, and restore the parts to their original condition, in readiness for the next operation. One of
 50 the advantages arising from this modified arrangement is that the rocking bails are relieved of the torsional strain which they would otherwise have to bear in transmitting the motion of the main reeds to the auxiliary reeds, except, of course, such strain
 55 as is involved in lifting the actuating slides B^{13} in tripping the cam yokes B^9 , which is altogether negligible.

Since the actuating reeds A^4 are themselves operated by power driven elements, it follows that the operating means for the auxiliary reeds include two sets of power driven elements, those of one set being set into action by the operation of the corresponding elements of the other set, and the keyboard controlling the action of the last

mentioned elements. Consequently, if in releasing matrices from an auxiliary magazine, the same finger key should be struck twice in rapid succession, there will be no danger of missing the second matrix, inasmuch as the main cam yoke will have completed its operation ahead of the auxiliary cam yoke, and in time to be set into action again by the actuation of the finger key for the second time. 75

As will be appreciated, when the matrices Z are released from an auxiliary magazine, they require more time for composition in line than do the matrices X , owing to the greater distance traveled to reach the assembler C^3 . Means are, therefore, provided for delivering spacers to the composed line in different periods of time to accord with the varying speeds of delivery of the matrices when drawn from the different magazines. In carrying out this phase of the invention, the spacers are stored, as customary, in a magazine F (Fig. 1) arranged at the left of the main magazines directly above the assembler C^3 , a guideway F^1 serving to convey released spacers from the magazine to the assembler. The release of the spacers from the magazine F is controlled, as usual, by means of an escapement F^2 operated by a long centrally pivoted lever F^3 connected at the right to a vertically movable rod F^4 . The rod F^4 is forked at its lower end so as to be operated by one or the other of two cam yokes F^5 , F^6 , provided with rotary cams F^7 , F^8 of different size and adapted 80 to cooperate in the usual way with the power driven rolls A^{10} . The two yokes are controlled in their operation by trip dogs F^9 , F^{10} , connected to the upper ends of actuating slides F^{11} , F^{12} , respectively. The slide F^{11} , which controls the operation of the cam yoke F^5 carrying the smaller cam F^7 , is operated by a finger key F^{13} which is arranged at the left side of the keyboard and is fast to a transverse rock shaft F^{14} , 85 having an arm F^{15} engaged with the slide. On the other hand, the slide F^{12} , which controls the operation of the yoke F^6 carrying the larger cam F^8 , is operated by a finger key F^{16} arranged at the right side of the keyboard and which is loosely mounted on the rock shaft F^{14} and is provided with an integral rearwardly extending arm F^{17} engaged with the slide. It may be stated that 90 the finger key F^{13} and the operating parts associated therewith are substantially the same as are ordinarily employed in operating the spacer escapement F^2 , so that when this particular finger key is struck, the spacers will be released from the magazine F in the usual period of time suitable for the composition of the matrices X from the main magazines. However, when the second finger key F^{16} is struck, the actuation 95 of the spacer escapement is somewhat de- 100

layed, due to the larger size or greater circumference of the cam F^s , and hence the spacers will be released from the magazine F more slowly or in a greater period of time 5 suitable for the composition of the matrices Z from the auxiliary magazines.

As previously stated, I have herein shown my invention only in preferred form and by way of example, and as applied to a machine of the class mentioned, and obviously many modifications and alterations therein, and in their mode of application, will suggest themselves to those skilled in the art without departure from its scope. I, 10 therefore, desire it to be understood that I do not limit myself to any specific construction or arrangement of the parts, except in so far as such limitations are specified in the 15 claims.

Having thus described my invention, its construction and mode of operation, what I claim and desire to secure by Letters Patent of the United States, is as follows:

1. In a typographical machine, the combination of a main magazine provided with escapements, an auxiliary magazine arranged at the side thereof and also provided with escapements, a set of actuating reeds adjustable into and out of operative relation to 25 the escapements of the main magazine, a second set of actuating devices arranged in constant operative relation to the escapements of the auxiliary magazine, and a series of transverse rocking bails for connecting the corresponding actuating reeds of the two sets, the said bails being constantly connected at one end to the actuating reeds of the auxiliary magazine, and arranged at 30 the opposite end to be directly engaged with and disengaged from the actuating reeds of the main magazine as said reeds are adjusted out of and into operative relation to their corresponding escapements, respectively.

2. In a typographical machine, the combination of a main magazine provided with escapements, an auxiliary magazine arranged at the side thereof and also provided with escapements, a set of actuating reeds adjustable into and out of operative relation to the escapements of the main magazine, and provided at their rear edges with projecting lugs, a second set of actuating reeds arranged in constant operative relation to 45 the escapements of the auxiliary magazine and also provided at their rear edges with projecting lugs, and a series of substantially U-shaped rocking bails located at the rear of the actuating reeds and adapted to connect the corresponding reeds of the two sets, the said bails having the arms at one end located below and in constant direct engaging relation to the lugs on the actuating reeds of the auxiliary magazine, and having the arms at the opposite end located above

the lugs on the actuating reeds of the main magazine and arranged to be engaged directly with and disengaged from said lugs as the reeds are adjusted out of and into operative relation to the corresponding escapements, respectively. 70

3. In a typographical machine, the combination of a main magazine provided with escapements, an auxiliary magazine arranged at the side thereof and also provided with 75 escapements, a set of pivoted operating levers arranged in constant operative relation to the escapements of the main magazine, a corresponding set of vertically movable actuating reeds adjustable into and out of direct engaging relation to said pivoted levers, a second set of vertically movable actuating reeds arranged in constant operative relation to the escapements of the auxiliary magazine, and a series of transverse 80 rocking bails for connecting the corresponding actuating reeds of the two sets, the said bails being constantly connected at one end to the actuating reeds of the auxiliary magazine and arranged at the opposite end to be 85 directly engaged with and disengaged from the actuating reeds of the main magazine, as said reeds are adjusted out of and into engaging relation to the pivoted operating levers of that magazine, respectively. 90

4. In a typographical machine, the combination of a main magazine provided with escapements, an auxiliary magazine arranged at the side thereof and also provided with escapements, two sets of escapement actuating reeds, one for each magazine, and a series of transverse rocking bails for connecting the corresponding actuating reeds of the two sets, the actuating reeds of the auxiliary magazine being arranged in constant operative relation to their corresponding escapements and the rocking bails, and an adjustable guide for the actuating reeds of the main magazine, the said guide acting in one 100 position to locate said reeds in operative relation to their corresponding escapements and out of engagement with the rocking bails, and acting in another position to locate said reeds out of operative relation to their corresponding escapements and in direct engagement with the rocking bails. 105

5. In a typographical machine, the combination of a main magazine provided with escapements, an auxiliary magazine arranged at the side thereof and also provided with escapements, two sets of escapement actuating reeds, one for each magazine, and a series of transverse rocking bails for connecting the corresponding actuating reeds of the two sets, the actuating reeds of the auxiliary magazine being arranged in constant operative relation to their corresponding escapements and the rocking bails, an adjustable guide for the actuating reeds of the main magazine, a spring acting constantly to hold 110 115 120 125 130

- the guide in one position to locate said actuating reeds in operative relation to their corresponding escapements and out of engagement with the rocking bails, and re-
5 leasable locking means for holding the guide in another position to locate said actuating reeds out of operative relation to their corresponding escapements and in direct engagement with the rocking bails.
- 10 6. In a typographical machine, the combination of a main magazine provided with escapements, an auxiliary magazine arranged at the side thereof and also provided with escapements, two sets of escapement
15 actuating reeds, one for each magazine, and a series of transverse rocking bails for connecting the corresponding actuating reeds of the two sets, the actuating reeds of the auxiliary magazine being arranged in con-
20 stant operative relation to their corresponding escapements and the rocking bails, an adjustable guide for the actuating reeds of the main magazine, and a finger key connected to the adjustable guide and operable
25 to set it in one or the other of two different positions, the said guide acting in one position to locate the actuating reeds in operative relation to their corresponding escapements and out of engagement with the rock-
30 ing bails, and in its other position to locate said reeds out of operative relation to their corresponding escapements and in direct engagement with the rocking bails.
7. In a typographical machine, the combination of a main magazine provided with escapements, an auxiliary magazine arranged at the side thereof and also provided with escapements, two sets of escapement actuating reeds, one for each maga-
35 zine, a series of motion transmission de-
40 vices for connecting the corresponding actuating reeds of the two sets, the actuating reeds of the auxiliary magazine being ar-
45 ranged in constant operative relation to their corresponding escapements and the motion transmission devices, and means for
50 adjusting the actuating reeds of the main magazine into and out of operative relation to their corresponding escapements and
55 out of and into engagement with the motion transmission devices, respectively, the said means including a finger key, connections therefrom to said actuating reeds for setting them in one of their different positions, and a spring acting upon the release of the finger key for setting the reeds in the other of their positions.
8. A combination as specified in claim 1, characterized by the fact that the rocking
60 bails therein recited are supported upon a smaller number of pivot rods, each of which is common to a plurality of bails.
9. A combination as specified in claim 1, characterized by the fact that the rocking
65 bails therein recited are mounted in a sup-
porting casing or box which is detachably connected to the framework so as to be applied to or removed from the machine as a unit.
10. A combination as specified in claim 1, characterized by the fact that the connections between the rocking bails and the actuating reeds of the auxiliary magazine include power driven elements set into action by the operation of the actuating reeds of the main magazine. 70
11. A combination as specified in claim 1, characterized by the fact that the actuating reeds of the main magazine are operated by power driven elements under the control of finger keys. 80
12. A combination as specified in claim 1, characterized by the fact that the actuating reeds of the main magazine are operated by power driven elements under the control of finger keys, and by the further fact that the connections between the rocking bails and the actuating reeds of the auxiliary magazine include power driven elements set into action by the operation of the actuating reeds of the main magazine. 85
13. In a typographical machine, the combination of a main magazine provided with escapements, an auxiliary magazine arranged at the side thereof and also provided with escapements, a set of actuating reeds for the escapements of the main magazine, means for adjusting said actuating reeds into and out of operative relation to their corresponding escapements, a second set of actuating reeds for the escapements of the auxiliary magazine, power driven elements for operating the reeds of the second set, and devices for controlling the action of said power driven elements, the said devices being arranged to be operatively engaged with and disengaged from the actuating reeds of the main magazine as they are adjusted out of and into operative relation to their corresponding escapements, respec- 95
100 tively. 105
14. In a typographical machine, the combination of a main magazine provided with escapements, an auxiliary magazine arranged at the side thereof and also provided with escapements, a set of actuating reeds for the escapements of the main magazine, means for establishing an operative or in-
110 operative relation between said reeds and escapements, a second set of actuating reeds for the escapements of the auxiliary magazine, power driven elements for operating the reeds of the second set, and devices for controlling the action of said power driven elements, the said devices being operated or unaffected by the actuating reeds of the main magazine according as there exists an operative or inoperative relation between said reeds and the escapements of that magazine. 115
120
- 125
- 130

15. In a typographical machine, the combination of a main magazine provided with escapements, an auxiliary magazine arranged at the side thereof and also provided with escapements, a set of actuating reeds for the escapements of the main magazine, a second set of actuating reeds for the escapements of the auxiliary magazine, two sets of power driven elements, one for each set of actuating reeds, finger keys controlling the operation of the power driven elements for the actuating reeds of the main magazine, and connections from the last mentioned actuating reeds controlling the 10 operation of the power driven elements for the actuating reeds of the auxiliary magazine. 70
16. In a typographical machine, the combination of a main magazine provided with 20 escapements, an auxiliary magazine arranged at the side thereof and also provided with escapements, a set of actuating reeds for the escapements of the main magazine, a second set of actuating reeds for the 25 escapements of the auxiliary magazine, two sets of power driven elements, one for each set of actuating reeds, finger keys controlling the operation of the power driven elements for the actuating reeds of the main 30 magazine, and connections through which said finger keys also control the operation of the power driven elements of the actuating reeds of the auxiliary magazine. 90
17. In a typographical machine, the combination of a matrix releasing escapement, and means for operating said escapement, the said means including two power driven elements, one set into action by the operation of the other, and a finger key controlling the action of the last mentioned element. 100
18. In a typographical machine, the combination of a main magazine provided with escapements, an auxiliary magazine arranged at the side thereof and also provided with escapements, a set of key-controlled actuating reeds for the escapements of the main magazine, a second set of actuating reeds for the escapements of the auxiliary magazine, power driven elements for operating the actuating reeds of the second set, and devices operated by the actuating reeds of the main magazine for controlling the action of said power driven elements. 110
19. In a typographical machine, the combination of two matrix magazines arranged side by side or in tandem, spacer storage means, means for assembling in line matrices from one or the other of the two magazines, and means under the control of the operator for delivering spacers to the composed line in different periods of time to accord with the varying speeds of delivery of the matrices when drawn from the different 60 magazines. 120
20. In a typographical machine, the combination of a main matrix magazine, an auxiliary matrix magazine, arranged at the right thereof, a spacer magazine arranged at the left of the main matrix magazine, means for composing in line matrices from their respective magazines, and means for delivering spacers from their magazine to the composed line in a greater or less period of time, according to the magazine from which the matrices are drawn. 75
21. In a typographical machine, the combination of a spacer magazine, an escapement therefor, and two independently operable finger keys for effecting the actuation of said escapement in different periods of time, for the purpose described. 80
22. In a typographical machine, the combination of a spacer magazine, an escapement therefor, two independently acting power driven elements for actuating said escapement in different periods of time, and means for initiating the operation of one or the other of the power driven elements, 85 as desired. 90
23. In a typographical machine, the combination of a spacer magazine, an escapement therefor, two independently acting power driven elements for actuating said escapement in different periods of time, and two finger keys operable to set into action one or the other of the power driven elements, according to the finger key operated. 95
24. In a typographical machine of the class described, the combination of a set of escapement actuating reeds for cooperation with a main magazine, a second set of escapement actuating reeds arranged at the side thereof for cooperation with an auxiliary magazine, a keyboard common to both sets of actuating reeds, and means whereby at least two different finger keys of the keyboard may be disconnected from the respective actuating reeds of the first set and connected to one and the same actuating reed of the second set. 100
25. In a typographical machine of the class described, the combination of a set of escapement actuating reeds for cooperation with a main magazine, a second set of escapement actuating reeds arranged at the side thereof for cooperation with an auxiliary magazine, a keyboard common to both sets of actuating reeds, and means whereby a plurality of pairs of finger keys of the keyboard may be disconnected from the respective actuating reeds of the first set and connected to a like plurality of actuating reeds of the second set, each of the latter reeds being common to the two finger keys of the corresponding pair. 115
26. In a typographical machine of the class described, the combination of a set of escapement actuating reeds for cooperation with a main magazine, a second set of 65 125 130

capement actuating reeds arranged at the side thereof for cooperation with an auxiliary magazine, connections between corresponding actuating reeds of the two sets, 5 certain reeds of the second set being common to different reeds of the first set, and means for making or breaking such connections, as desired.

27. In a typographical machine, the combination of a main magazine provided with escapements, a plurality of auxiliary magazines arranged at the side thereof and also provided with escapements, a set of escapement actuating reeds for the main magazine, 10 a second set of escapement actuating reeds for the auxiliary magazines, means for establishing an inoperative relation between the first set of actuating reeds and the escapements of the main magazine, means for 15 establishing an operative relation between the second set of actuating reeds and the escapements of either of the auxiliary magazines, and devices for connecting the corresponding actuating reeds of the two sets, 20 certain of the reeds of the second set being common to different reeds of the first set.

28. In a typographical machine, the combination of a main magazine provided with escapements, a plurality of auxiliary magazines arranged at the side thereof and also provided with escapements, a set of escapement actuating reeds for the main magazine, a second set of escapement actuating reeds for the auxiliary magazines, means for establishing an inoperative relation between the first set of actuating reeds and the escapements of the main magazine, means for shifting the auxiliary magazines to bring the escapements of either into operative relation to the second set of actuating reeds, and devices for connecting the corresponding 30 35 40

actuating reeds of the two sets, certain of the reeds of the second set being common to different reeds of the first set.

29. In a typographical machine, the combination of a main magazine provided with escapements, a plurality of auxiliary magazines arranged at the side thereof and also provided with escapements, a set of escapement actuating reeds adjustable into and out of operative relation to the escapements of the main magazine, a second set of escapement actuating reeds, means for shifting the auxiliary magazines to bring the escapements of either into operative relation to the actuating reeds of the second set, and devices for connecting the corresponding actuating reeds of the two sets, certain of the reeds of the second set being common to different reeds of the first set. 45 50 55 60

30. In a typographical machine, the combination of a main magazine provided with escapements, a plurality of auxiliary magazines arranged at the side thereof and also provided with escapements, a set of escapement actuating reeds adjustable into and out of operative relation to the escapements of the main magazine, a second set of escapement actuating reeds, means for shifting the auxiliary magazines to bring the escapements of either into operative relation to the actuating reeds of the second set, and a series of transverse rocking bails for connecting the corresponding actuating reeds of the two sets, certain of said bails being each formed to engage different actuating reeds of the first set and one only of the second set. 65 70 75

In testimony whereof, I have affixed my signature hereto.

DAVID S. KENNEDY.
